(57) **CLAIM**

We claim the ornamental design for a light-emitting diode, as shown and described.

DESCRIPTION

FIG. 1 is a top perspective view of a light-emitting diode of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken line showing of light-emitting diode is included for the purpose of illustrating environment and forms no part of the claimed design. Additionally, the unevenly broken lines in the drawings define the limits of the claimed design.

The transparent dome is formed with a substantially conical recess at its top portion.
